UNITED STATES PATENT OFFICE.

HJALMAR TANTTILA, OF CHICAGO, ILLINOIS, AND JOHN SOROLA, OF CROSBY, MINNESOTA, ASSIGNEES OF ONE-THIRD TO PETER HOLAPPA, OF CHICAGO, ILLINOIS.

RAILWAY SWITCH.

1,427,563.

Specification of Letters Patent. Patented Aug. 29, 1922.

Application filed December 5, 1921. Serial No. 520,202.

To all whom it may concern:

Be it known that we, HJALMAR TANTTILA and JOHN SOROLA, citizens, respectively, of the United States and Finland, and residents, respectively, of Chicago, in the county of Cook and State of Illinois, and Crosby, in the county of Crow Wing and State of Minnesota, have jointly invented certain new and useful Improvements in Railway 10 Switches, of which the following is a specification.

This invention relates to improvements in railway switches and its object is to provide a switch which may be thrown by manually 15 operated means to run the train upon a siding and then, by the same means, thrown to permit a train to travel over the switch upon the main line in a direction away from the siding and immediately thereafter the train 20 upon the siding may pass out upon the main line without the switch being opened by hand, and said train may again pass over the switch past the siding.

With the foregoing and other objects in 25 view the invention consists in the combination and arrangement of parts to be herein-after fully described, pointed out in the appended claims and illustrated in the accompanying drawings which form a part of this

30 application and in which—

Fig. 1 is a plan view with the switch closed.

Fig. 2 is a similar view with the switch open.

35 Fig. 3 is a section taken on line 3—3 of Fig. 1.

Fig. 4 is a section taken on line 4—4 of Fig. 1.

40 Fig. 5 is a section taken upon line 5—5 of Fig. 1.

Fig. 6 is a perspective view of the guide rail.

Like reference characters denote corresponding parts throughout the several views.

45 The reference numerals 1, 2 designate stock rails of the standard type, 3 and 4 the switch rails and 5 is a guide rail. A bolt 6 secured to the switch rail 3 near its point extends into a telescoping casing 7 and at its 50 free extremity, which projects beyond the end of said casing, is provided with a nut 8. About the bolt within the casing a spring 9 is disposed which normally tends to force the sections of the casing away from each

other or to keep the casing extended. The 55 end of the bolt 6 remote from the rail 3 is supported in an angle iron 10 which is secured to a pitman 11 that is supported in guide brackets 12, 12 secured to and depending from the stock rails, and said pitmen is 60 formed with or carries a lug 13 adapted for engagement with the guide-rail 5; the pitman 11 is connected by the link 14 with the foot 15 of the manually operated switch lever 16. 65

17 denotes a bolt secured to the stock rail 1 and extending through the guide rail 5 and casing 18 and supported by the standard 19 secured to a rail tie 20. The casing 18 is open at one end and in the open end a nut 20a is disposed upon the bolt 17 and a spring 21 within said casing abuts the closed end of the same and the nut and tends to force the casing away from the said nut, together with the guide rail 5. A bolt 22 secured to 70 the switch rail 4 extends through the guide rail 5 and into a casing 23 and said bolt is supported by a standard 24 secured to a rail tie 20; in the open end of the casing 23 a nut 26 is disposed upon the bolt and a spring 80 27 abuts the same and the closed end of the casing and tends to move said casing and guide rail toward the switch rail 1.

Referring to Figure 4 of the drawings it will be apparent that as the member 11 is 85 moved to the left, transversely to the rails, the member 10 through the medium of the spring 9 will force the switch rail 3 against the rail 2 as shown in Fig. 1. This leaves the main line open and thus the movement 90 of the member 11 in conjunction with the spring members 7 and 26 control the movement of the switch rails 3 and 4.

Operation:—In case trains running in opposite directions upon the standard rails approach each other at the siding, the switch may be thrown open to permit the train approaching the siding to enter upon the same; after which it is closed by the operator or switchman. The other train now runs over 95 the switch and continues upon its journey. With the switch still in closed position the train upon the siding now backs upon the main line, the flanges of the wheels forcing the switch rail and guide rail away from the 100 stock rails against the tension of the several springs 9, 21, 27 which springs instantly 105 close the switch after the wheels have passed

so that the train can resume its journey without the necessity of manual operation of the switch.

What is claimed is:—

5. The combination with the rails of the main line, one of which is intersected by a pivotal rail, which forms a continuation of the main line rail, of a rod transversely slideable thereunder, switch rails, the one adjacent to said pivotal main line rail being a continuation of said main line rail, the other being pivotally connected to the remaining switch rail, a guide rail lying adjacent to said last mentioned switch rail and having 15 its upper end pivoted in juxtaposition with said pivotal switch rail, a spring buffer normally holding the free end of the pivotal rail of the main line in position to close the

main line, a retraction spring connected with and normally holding the remaining switch point and guide rail against the main line so as to close that rail of the main line, abutments on said rod engaging said buffer and said pivotal switch rail, and means for shifting said rod to open said main line. 20 25

In testimony that we claim the foregoing as our own we have hereto affixed our signatures in the presence of subscribing witnesses.

HJALMAR TANTTILA.

JOHN SOROLA.
